UNITED STATES PATENT OFFICE.

HARVEY C. LOWRIE, OF DENVER, COLORADO.

RAILROAD-CROSSING.

SPECIFICATION forming part of Letters Patent No. 398,269, dated February 19, 1889.

Application filed September 22, 1888. Serial No. 286,083. (No model.)

To all whom it may concern:

Be it known that I, HARVEY C. LOWRIE, of Denver, in the county of Arapahoe, in the State of Colorado, have invented certain new and useful Improvements in Railroad-Crossings; and I do hereby declare that the following specification, taken in connection with the drawings furnished and forming a part of the same, is a clear, true, and complete description 10 of my invention.

It is well known that grade-crossings are so attended with danger and delays that public sentiment has demanded their discontinuance wherever it has been deemed practicable to 15 substitute bridges or cuts, or both, for crossings at surface-grade. So far as my knowledge extends, grade-crossings in low-level localities have generally been heretofore employed, and especially so at points where railroads 20 cross others, because of the impracticability of an ordinary cut, as well as of the elevated grade necessary for crossing a road which is not depressed below the average surface-line of the ground traversed by the road. It is 25 also well known that most low-level regions—such as river-bottoms and low-lying lake-prairies—have water-bearing strata so near the surface-grades that any substantial depth of cut would develop a water-trench, and even 30 if at times such a cut should not directly drain adjacent ground it would be liable to be flooded by heavy rain-storms.

The object of my invention is to practically overcome these difficulties, and I do this by 35 excavating at a railroad-crossing a gradually-developed cut below the surface-grade and having the desired depth at the crossing-point, and providing said cut or road-bed depression with water-excluding side walls and bottom, 40 and also with a drainage tank or well at its lowest point, from which ground-water is excluded and into which storm-water will be drained, and from which it may from time to time be withdrawn by suitable means provided for that purpose.

To more particularly describe my invention, I will refer to the accompanying drawings, in which—

Figure 1 illustrates in plan view my invention as applied to the crossing of two railroads. Fig. 2 illustrates the grade of the gradually-developed cut for the lower road and the ele-

vation of the upper road at the point of crossing. Fig. 3 illustrates in longitudinal section the central portion of the cut, and also in 55 cross-section the upper roadway. Fig. 4 illustrates in cross-section the central portion of the cut and also a portion of the upper roadway.

As here shown, I will term the road A the 60 "lower road," and the bridge B the roadway for the upper, it being understood that this latter may be a country road or street or a railroad without in any manner affecting my invention. It is to be assumed, however, that 65 the location of the crossing is in a locality which would preclude an ordinary cut below surface-grade for the lower road, because of the liability of such a high-water level as would obviously convert the cut into a water- 70 ditch, and such a water-level is indicated at the dotted line a.

The cut C for the lower road is gradually developed at an easy incline from each end below the surface-grade until the required 75 depth is attained, this depth being of course varied according to circumstances—as, for instance, if the lower road be depressed at the crossing to the extent of one-half the height needed to afford proper head-room for passing 80 trains and the upper road be elevated one-half of said needed height both roads, as a rule, would fairly share whatever disadvantages might accrue from their respective variations in grade above and below the surface- 85 grade; but these variations would of course be subject to concessions and agreement in each case where different interests were involved. If, however, the lower road should bear the entire burden of grade variation, as 90 may sometimes be necessary, the value of my invention would be all the more apparent.

The length of the cut C will of course be widely varied according to the character and extent of traffic on the lower road, and hence 95 no rule of grade into and from the cut can be definitely determined, and the same is true of the width of the cut; but in all cases the side walls, b, and bottom c of said cut are as nearly water-tight as possible; or, in other 100 words, as capable as possible of excluding water which would otherwise enter the cut from adjacent ground. These walls and the bottom may be composed of any available variety of

brick or stone masonry with good cement, and, in lieu of such materials, timber can be employed when adapted to afford tight joints with or without the aid of calking, pitching, or cementing, and so, also, may iron plates be used, if properly united—as, for instance, by riveting—but, as a rule, masonry in good cement will prove most desirable.

Having thus provided for the exclusion of earth-water from the cut, I further provide for the control of such storm-water as the cut, if left open, must naturally receive by constructing at the center of the cut, and at its lowest point a drainage well or tank, D, accessible through one or more proper openings in its top to such storm-water as the cut may receive from time to time. This drainage-tank should in some cases be first constructed so that it may afford opportunity for pumping water therefrom during the making of the cut and putting in the water-tight side walls and bottom, and hence I prefer that said tank be complete in itself and constructed of wood or of iron, and provided with a series of holes, *d*, in its side walls, so that water may enter otherwise than at its top until the cut is completed, and then said holes are tightly plugged, thus excluding all except such storm-water as may fall into the cut from time to time, care being taken to provide water-tight joints at the junction of the top of the tank or cistern with the water-tight bottom *c* of the cut. In such localities as will warrant the use of snow-sheds the latter may be relied upon for also excluding storm-water from the cut, thus rendering the drainage-tank of little, if any, practical value.

As thus far described, it will be seen that I amply provide for railroad-crossings at different grades, regardless of those conditions which have heretofore made crossings at grades seemingly imperative. The expense of my water-tight cuts will of course be considerable; but, as I believe, the practical advantages incident thereto greatly outweigh the matter of initial expenditure, in view of the absence of danger to life and property, as well as the attendant economy in time, es-

pecially in those States wherein by law trains before crossing another railroad must be brought to a full stop. The removal of water from the drainage-tank will be frequently necessary in some localities, while in others, where rain or snow seldom falls and then only in small quantities, the tank may be large enough to require no emptying, and hence means for pumping are not essential elements in my invention, although in most cases local pumps operated by steam-power or by wind-mills will be used, although a siphon-pump operated by steam from a locomotive at rest over the tank may be used for transferring the water to the tender. So, also, may the tank be provided with such plugs or gates in its side walls as may be readily opened and closed, so that in wet localities the tank may serve as a watering-station, if a steam siphon- or other form of pump be used on the locomotive. In specially wet localities I deem it advisable to surround the entire cut with one or more lines of water-ditches, with a view to collecting water therein for exposure to evaporation.

Having thus described my invention, I claim as new and desire to secure by Letters Patent—

1. The improvement in railroad-crossings, which consists in a gradually-developed cut or road-bed depression below surface-grade to a required depth, and having water-tight walls and bottom and also having a drainage tank or well, in combination with a roadway-bridge crossing said cut at such a point thereof as will best afford proper head-room below said bridge for trains passing through said cut.

2. As a means for obviating surface-grade crossings on railroads traversing low-level wet localities, a gradually-developed cut or road-bed depression, in combination with side walls and a bottom for said cut which exclude water from entering said road-bed depression from the adjacent ground, substantially as described.

HARVEY C. LOWRIE.
